UNITED STATES PATENT OFFICE.

HUGO HÜCKEL, OF NEUTITSCHEIN, AUSTRIA-HUNGARY.

SLIDE-VALVE GEAR FOR FOUR-STROKE EXPLOSIVE-ENGINES.

1,173,970.

Specification of Letters Patent. Patented Feb. 29, 1916.

Application filed May 5, 1914. Serial No. 836,513.

To all whom it may concern:

Be it known that I, Hugo HÜCKEL, a subject of the Austrian Emperor, and resident of Neutitschein, Austria-Hungary, have invented certain new and useful Improvements in Slide-Valve Gear for Four-Stroke Explosion-Engines, of which the following is a specification.

This invention relates to valve gears for 10 gas engines, and is adapted to improve upon the construction shown in my prior Patent, No. 1,088,580, dated February 24th, 1914.

The primary object of this invention is to provide a slide valve located in one end of 15 the gas engine cylinder, and is so constructed as to form a cylinder which may be operated to admit a charge or to exhaust the spent charge.

A further object of this invention is to 20 provide a valve mechanism which shall vary the area of the cylinder during the charging and exhausting periods, in order to obtain the most effective results.

With these and other objects in view, this 25 invention consists in the peculiar combination and arrangement of the various parts of a slide valve gear, as will be hereinafter described and more particularly set forth in the appended claim.

30 Referring to the drawings forming a portion of this application, wherein similar reference numerals indicate similar parts wherever used the figure is an axial section through a motor embodying my improved 35 device.

The numeral A represents the cylinder housed at its upper end by a casing A', which forms a chamber A². Below the casing A' the cylinder is provided with an annular exhaust chamber K, having an exit K' to the outer air.

40 Communicating with the exhaust chamber and the cylinder A, are outlet openings d. The top end a is closed by means of a transverse wall u, provided with a central aperture, through which extends a hollow member 1, which is provided on its lower end with a plurality of radial arms v, which support the cylindrical slide valve 2 and on 45 its outer end with a bolt w having a central aperture with outwardly extending members z¹ and z², which are connected by means of a stirrup member j, in order to hold the guides rigid.

50 Mounted in suitable bearings in casing A'

is a horizontal shaft a, to which is secured an eccentric b. This eccentric is hollow and is open at its ends to communicate with a port m³, which communicates through the medium of the port p with the combustion chamber of the cylinder a. Surrounding the periphery of the eccentric is a band or casting c, the lower portion or base of which is provided with lateral flanges 3 and 4, adapted to rest upon the bolt w, as shown, and also further provided with flanges 5 and 6 resting upon the stirrup member j. In operation the parts are so timed that when the working piston w descends to stick in the charge the eccentric will operate to move the 55 slide valve 2 in the opposite direction and close the ports d—d of the exhaust port K, and at the same time, the inlet port m³ will register with the inlet port p, and permit a charge to be drawn in through the suction pipe 75 7. The return stroke of the piston will compress the charge, and the latter will be freed by the spark plug n at the proper moment, and then upon the next upstroke of the piston, the eccentric b will move the slide valve 80 2 so as to bring the exhaust ports into communication with the cylinder, which will be purged.

By the construction described, the air of the cylinder at the time the gas is freed, is 85 greater than that during the period of exhaust of the spent gases, which produce a much more effective action upon the piston and a much more effective exhaust action.

I claim—

In a slide valve gear for explosion engines, the combination with the cylinder and the stationary head thereof, of an exhaust port provided in the circumferential wall of the said cylinder, an annular piston valve 95 adapted to move in the said cylinder and to control the said exhaust port, a central hole being provided in said cylinder head, a suction pipe suitably engaged in said hole, a plurality of arms connecting said suction pipe at its lower end with said piston valve, a slide face carried by the upper end of said suction pipe, an inlet port in said slide face, an eccentric above the said slide face, an eccentric strap for said eccentric, a basis on 100 said eccentric strap and adapted to cooperate with said slide face, an inlet port in said basis, and an inlet duct in said eccentric, guides positioned at right angles to said slide face and rigidly connected with the 110

latter, a transverse member (j), connecting the outer ends of said guides and adapted to present a slide surface, and a slide member provided on the outer side of said eccentric strap and adapted to coöperate with said transverse member, substantially as and for the purpose set forth.

In testimony whereof I have hereunto set my hand in presence of two witnesses.

HUGO HÜCKEL.
